Pietro Cingini of Meriden Conn.

Assign to

John E. Parker & Co. & P. Whipple of Meriden Conn.
Letter Patent No. 3416 Dated Mar. 7. 1865.

Design for a Drawer Pull.

The Schedule referred to in these Letters Patent and making part of the same.

To all whom it may concern,

Be it known that I, Pietro Cingini a subject of the Kingdom of Italy, now residing in Meriden, in the County of New Haven, and State of Connecticut have produced a new and Original Design for Metal Draw Pull; and I do hereby declare the following, where taken in connection with the accompanying drawings and the letters of reference marked thereto, to be a full, clear and exact description of my Design and which said drawings constitute part of this Specification and represent my Design in a true view,

The article commonly called a "Drawer Pull," to which my Design relates, is used as a substitute for knobs for drawers or whenever a handle is required, by means of which to move the thing to which such Pull is secured. In the clear understanding of my Design, I will describe the same, as illustrated in the accompanying drawings.

The upper edge A, is made floriated, a leaf springing from a Henry leaf center terminates at the stem of another leaf which forms a hole C, for the insertion of a screw. The lower edge B, springing from the

DES. 2216

2 lower corners, swells from the plane of the pull to form a recess for the insertion of the fingers; the space between the upper and lower edges is filled with diamond open work supporting in the center a shield; this completes the Design which I desire to secure by Letters Patent. - I therefore claim the design for Drauer Pulls as fully shown and described.
